UNITED STATES PATENT OFFICE.

PERCY D. CANHAM, OF NEW YORK, N. Y., ASSIGNOR TO POWER SPECIALTY COMPANY,
OF NEW YORK, N. Y., A CORPORATION OF NEW YORK.

DESTRUCTOR-FURNACE.

1,066,184.

Specification of Letters Patent.

Patented July 1, 1913.

Application filed October 5, 1910. Serial No. 585,386.

To all whom it may concern:

Be it known that I, PERCY D. CANHAM, a subject of the King of Great Britain, residing at New York, county of Richmond, 5 and State of New York, have invented certain new and useful Improvements in Destructor-Furnaces, of which the following is a full, clear, and exact description.

In the operation of so-called "destruct- 10 tor" furnaces the material consumed is, in general, refuse, such as household and city waste, wet and dry, inflammable and non-inflammable, and is of low calorific value. This makes it specially important 15 that the furnace operate with the highest efficiency, making the greatest possible amount of the heat available for useful purposes, with the least possible loss. To this end it is desirable that the heat remaining 20 in the clinker, after the combustible material has been consumed, be utilized. The usual way of utilizing such heat is to employ it for heating the air which supports the combustion, and it is to this method of 25 utilization that my present invention generally relates, its chief object being to provide improved means for handling the clinker in a convenient and expeditious manner, and for disposing of it in such way as 30 to cause its heat to be rapidly and efficiently imparted to the air furnished to the burning mass on the combustion grate or in the grate chamber.

To this and other ends the invention con- 35 sists in the novel features of construction and combinations of elements hereinafter described, and more particularly set forth in the claims.

A convenient and effective embodiment of 40 the invention is illustrated in the accom- panying drawings, in which—

Figure 1 is a sectional plan view, on line 1—1 of Fig. 2, of a destructor furnace in which my invention is employed. Fig. 2 is 45 a sectional side view.

The furnace illustrated comprises a series of grate chambers, one being shown at 12, arranged side by side and each communicating 50 with the adjoining chambers through suitable openings, one of which is shown at 13, so that the products of combustion can flow from one chamber to the next, in succession, finally reaching the stack or outlet flue, not shown. The bottom of each grate chamber is 55 formed by a grate on which the burning of

the refuse takes place, each combustion grate being preferably of the type described in the application of E. H. Foster, Serial No. 539,103, filed January 20, 1910, and J. T. Fetherston, Serial No. 541,504, filed February 2, 1910. In grates of this type, as illustrated, the grate, for example that shown at 14, is slidably mounted on anti-friction rollers 15, journaled in rails, as 16, at the sides of the clinker-pit 17 near the top there- 60 of. Connected to the movable grate is the plunger 18 of a suitable fluid-pressure ram 19, by which the grate may be actuated. In the present form the ram is in front of the furnace, and the lower front wall 20 of the 65 grate chamber is substantially vertical, so that as the grate is retracted or drawn out from under the grate chamber such vertical wall will scrape the clinker off and into the clinker-pit below. An air-tight chamber 39 70 is employed to receive the grate when the latter is retracted from under the grate chamber. 75

The mouth 21 of the grate chamber is provided with a vertically movable door 22, 80 connected with suitable counter-weights, not shown, and in front of the chamber mouth is a charging apparatus of the type described in the application of J. T. Fetherston, Serial No. 541,503, filed February 2, 1910, comprising a pan or receptacle 23, movable into and out of the furnace, on suitable supporting rollers and rails, by means of a fluid pressure ram the plunger of which is shown at 24.

To charge the furnace the pan is filled with 90 the material to be burned and is advanced into the grate chamber. The pan is then retracted, but the wall 25 thereof is held stationary during part, at least, of such movement, thereby causing the material in 95 the pan to be dislodged over the opposite edge, on to the combustion grate.

The bottom of the clinker pit is formed by a grate 26 upon which the clinker falls as it is dislodged from the moving combustion grate 14. Below the clinker grate is an air chamber 27, connected at its rear, by means of a passage 28, with an air-duct 29 through which a current of air is caused to flow by any suitable means not shown. In 100 the passage 28 is a damper or valve 30 by which the flow of air to the air chamber may be regulated. The clinker grate being cov- 105 ered with lumps or pieces of clinker of various sizes, it will be seen that the air, flow- 110

ing up through the grate openings and the
clinker, will be highly heated before reaching
the combustion grate; the result being
that the combustion on the latter grate is
5 more rapid and thorough than would be the
case if the air were supplied cold or only
moderately heated.

At one end of the clinker-pit, for example
the rear, is a fluid pressure ram 31, the plun-
10 ger 32 of which is connected to a scraper 33
movable over the clinker grate. As the plun-
ger is advanced the scraper pushes the
clinker off the grate through the front open-
ing of the pit and over a shelf or lip 34 into
15 a car 35 by which the clinker is carried to
the dump. The front opening, or mouth, of
the clinker-pit is provided with a suitable
door 36, in the present instance hinged at
one side, by which the clinker pit mouth is
20 closed except while the car is being loaded.
The air chamber below the clinker grate may
be provided with a clean-out opening 37,
normally covered by a removable closure 38.

The apparatus described is, as will be
25 recognized, an efficient means for handling
and disposing of the clinker for the purpose
before mentioned, the clinker being de-
posited on the clinker grate expeditiously
and with practically no loss of heat. After
30 the heat of the clinker has been imparted to
the air flowing through the clinker it is
rapidly delivered to the car, leaving the
clinker grate clear and ready for another
load from the combustion grate.

35 The embodiment described is, as just stated,
efficient, and is also simple in construction
and convenient in operation, but it is to be
understood that the invention may be em-
bodied in other forms without departure
40 from its proper spirit and scope as defined
by the appended claims.

I claim:

1. In a destructor furnace, a grate cham-
ber, a horizontally reciprocating grate there-
45 in adapted to support all refuse which is
substantially consumed thereon, an air-tight
chamber located outside of the grate cham-
ber and adapted to receive the grate when
the latter is retracted from under the grate
50 chamber, a clinker pit below said grate cham-
ber, said reciprocating grate discharging hot
clinker into said clinker pit, a clinker grate
in said clinker pit, an air chamber below said
clinker grate, means for supplying air to
55 said air chamber, said air passing through
the clinker grate and the clinker and becom-
ing highly heated thereby, and a power actu-
ated means for discharging cooled clinker
from the clinker grate.

60 2. In a destructor furnace, a grate cham-

ber, a horizontally reciprocating grate there-
in adapted to support all refuse which is
substantially consumed thereon, an air-tight
chamber located outside of the grate cham-
ber and adapted to receive the grate when 65
the latter is retracted from under the grate
chamber, a clinker pit below said grate
chamber, a clinker grate in said clinker pit,
means for reciprocating the first mentioned
grate horizontally into the air-tight cham- 70
ber to distribute hot clinker from the grate
chamber upon said clinker grate, means lo-
cated between the furnace grate and the
clinker grate to discharge the clinker from
the latter, means passing through the walls 75
between the grates to operate the aforesaid
means the walls between said grates having
an opening through which the clinker is dis-
charged from the pit by the aforesaid means,
an air chamber below said clinker grate, and 80
means for supplying air under pressure to
said air chamber, whereby said air passes
through the clinker grate and the hot clinker
thereon and becomes highly heated thereby.

3. In a destructor furnace, in combination, 85
a grate chamber in which the combustion
takes place, a horizontally reciprocating
grate in said grate chamber, a clinker pit in
substantially vertical alinement with and be-
low the grate chamber, an air-tight chamber 90
located outside of the grate chamber and
adapted to receive the grate when the latter
is retracted from under the grate chamber,
means for retracting the grate from the
grate chamber into said air-tight chamber 95
to discharge hot clinker from the grate
chamber into the clinker pit, the walls of
said clinker pit provided with a lateral open-
ing through which the clinker is discharged
from the clinker pit, a scraper arranged 100
above the clinker grate and movable there-
over in line with the discharge opening of
the clinker pit, a power actuated means pass-
ing through the walls of the clinker pit for
advancing the scraper whereby the cooled 105
clinker is scraped off the clinker grate and
through said opening out of the clinker pit,
an air chamber below the clinker pit and
in substantially vertical alinement with the
grate chamber and clinker pit, and means 110
for supplying air to the air chamber, said air
passing through the clinker grate and the
clinker and becoming highly heated thereby.

In testimony whereof I affix my signature
in the presence of two subscribing witnesses. 11
